FIG. 3

JAMES INVENTOR
ROBINSON

BY

Ralph L. Tweedale
ATTORNEY

UNITED STATES PATENT OFFICE

123,005

DESIGN FOR A POWER TRANSMISSION

James Robinson, Detroit, Mich., assignor to Vick-
ers Incorporated, Detroit, Mich., a corporation
of Michigan

Application February 15, 1940, Serial No. 90,289

Term of patent 14 years

To all whom it may concern:

Be it known that I, James Robinson, a citizen of the United States of America, residing at Detroit, in the county of Wayne and State of Michigan, have invented a new, original, and ornamental Design for a Power Transmission, of which the following is a specification, reference being had to the accompanying drawing, forming a part thereof.

In the drawing:

Figure 1 is a plan view of a power transmission, showing my new design.

Figure 2 is a side elevational view thereof.
Figure 3 is an end elevational view thereof.

I claim:

The ornamental design for a power transmission, as shown.

JAMES ROBINSON.
